Primary Examiner — Elizabeth J Oswecki(74) *Attorney, Agent, or Firm* — Woods Oviatt Gilman LLP; Dennis B. Danella, Esq.(57) **CLAIM**

The ornamental design for the fire-resistant safe, as shown and described.

DESCRIPTION

FIG. 1 is a front perspective view of a fire-resistant safe showing our new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a back view thereof; and;

FIG. 8 is a back perspective view thereof.

The portions of the drawings shown in broken lines form no part of the claimed design.
